CLAIM

The ornamental design for a razor cartridge, as shown and described.

DESCRIPTION

FIG. 1 is a perspective view of a razor cartridge or the present design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines immediately adjacent the shade lines represent the bounds of the claim. The remaining broken lines illustrate portions of the article. None of the broken lines forms part of the claimed design.

It is understood that in FIGS. 1-7, the figure shading with lighter stipple shading represents a first color and the figure shading with darker stipple shading represents a second contrasting color.
